ATTORNEY.

UNITED STATES PATENT OFFICE.

THEODORE P. SCHOTT, OF PANAMA CITY, FLORIDA.

DESIGN FOR A FOOTREST.

58,946.

Specification for Design.

Patented Sept. 6, 1921.

Application filed June 5, 1920. Serial No. 386,819. Term of patent 14 years.

To all whom it may concern:

Be it known that I, THEODORE P. SCHOTT, a citizen of the United States, residing at Panama City, in the county of Bay and State of Florida, have invented a new, original, and ornamental Design for a Footrest, of which the following is a specification, reference being had to the accompanying drawing, forming part thereof.

The figure is a perspective view of my new design.

I claim:

The ornamental design for a footrest as shown.

THEODORE P. SCHOTT.
